UNITED STATES PATENT OFFICE.

WILLIAM HILLMAN, OF COVENTRY, COUNTY OF WARWICK, ENGLAND, AS-SIGNOR TO HILLMAN, HERBERT & COOPER, (LIMITED,) OF SAME PLACE.

VELOCIPED.

SPECIFICATION forming part of Letters Patent No. 430,019, dated June 10, 1890.

Application filed March 18, 1890. Serial No. 344,409. (No model.) Patented in England November 17, 1888, No. 16,736, and in Germany January 25, 1889, No. 48,990.

To all whom it may concern:

Be it known that I, WILLIAM HILLMAN, a subject of the Queen of Great Britain, residing at Coventry, in the county of Warwick, England, have invented certain new and useful Improvements in Velocipedes, (for which I have obtained patents in England, dated November 17, 1888, No. 16,736, and Germany, dated January 25, 1889, No. 48,990;) and I do hereby declare that the following is a full, clear, and exact description of the invention, which will enable others skilled in the art to which it appertains to make and use the same.

The invention relates to improvements in the construction of that class of Safety-bicycle frame which is known as the "diamond-shaped frame;" and it consists in building up such frames of trough-shaped or crescent-section steel, such as that used for the felloes of wheels.

My invention is illustrated in the accompanying drawings, in which—

Figure 1 represents a Safety bicycle with parts thereof constructed according to my invention showing a side view of the complete machine, except that the saddle is not shown. Fig. 2 is a sectional plan thereof drawn on the line 1 1 of Fig. 1, but omitting the brake and spokes and rims of the wheels. Fig. 3 is a vertical section of front part of diamond-shaped frame. Fig. 4 is an elevation, as seen when looking forward, of the front part of the frame detached from the back part and from the mud-guard. Fig. 5 is a plan drawn on the line 2 2 of Fig. 3. Fig. 6 is a plan drawn on the line 3 3 of Fig. 3, and Fig. 7 is a section on the line 4 4 of Fig. 5. Fig. 8 is a vertical section of the back part or forks of the diamond-shaped frame. Fig. 9 is a plan of the upper bars thereof, and Fig. 10 is a sectional plan of Fig. 8, drawn on the line 5 5. Figs. 3 to 10 are drawn to double the scale of Figs. 1 and 2.

In all the figures like parts are indicated by similar letters of reference.

A is the front or steering wheel. B is the rear or driving wheel. C is the crank-axle. C' are the cranks. C² is the crank-chain wheel.

C³ are the pedals. D is the driving-axle. D' is the chain-wheel thereon. E is the steering-head. E' is the front fork. F is the brake and brake-levers. G are the steering-handles. H is the diamond-shaped frame, and I is the seat-pillar.

The diamond-shaped portion of the frame H is formed of four lengths or bars h h' h² h³, of trough-shaped or felly steel, on each side arranged with the hollows thereof inward or toward each other and nearly meeting at the forward end or neck h⁴, to which they are connected by means of arms h⁵, stamped or forged in one piece with the neck and fitting within the grooves of the bars h h², to which they are brazed. The bars h h² are fixed together in pairs by means of distance-pieces h⁶, fitting within the hollows thereof and brazed thereto, by which means rigidity and strength of frame are secured. The bars h are connected together at the upper angle of the frame and to the bars h' by means of the forging or stamping h⁷, having arms h⁸, fitting the hollows of the respective pairs of bars h and h' and brazed thereto. A cross-bar or mud-guard h⁹, made of larger section metal than that used for the bars h h' h² h³, connects the top and bottom angles of the diamond-shaped frame by means of the forgings or stampings h⁷ h¹⁰ h¹⁴ in the following manner:

The forging or stamping h⁷ is fitted around and brazed to the cross-bar or mud-guard h⁹. The forging or stamping h¹⁰ has arms h¹¹, fitting and brazed within the hollows of the bars h², and it is formed with arms h¹³, fitting around and brazed to the cross-bar or mud-guard h⁹, and the forging or stamping h¹⁴ is formed with an arm h¹⁵, fitting within and brazed to the cross-bar or mud-guard h⁹, and with arms h¹⁶ fitting within and brazed to the hollows of the bars h³. The forging or stamping h¹⁴ is also formed with a bearing h¹⁷, to carry the pin or axis of the lug or arm h¹⁸ of the crank-shaft bearing, and with a perforated lug h¹⁹, through which the chain-tension-regulating screw or bolt h²⁰ passes.

The bars h' h³ on each side of the frame are connected at the rear end by means of a

forging or stamping h^1 , having arms or projections h^2 , fitting within and brazed to the hollows of the bars h' h^3 . Thus the bars h' h^3 of the diamond-shaped frame form a pair 5 of forks, which are connected together on each side by means of the forgings or stampings h^1 , which are also formed with bearings h^2 to carry the axle of the driving-wheel B.

- The upper end of the cross-bar or mud- 10 guard h^9 is extended beyond the diamond- shaped frame and is forged into the form of a tube h^{24} , and it has brazed thereto at its upper end a collar h^{25} , formed with lugs h^{26} , which are held together by a screw-bolt, so as 15 to be capable of receiving and adjustably holding the seat-pillar I within the tube h^{24} . The upper end of the mud-guard or cross- bar may, however, be otherwise formed or fitted to receive a seat or saddle.
- 20 Instead of using trough-shaped or felly steel in the construction of the cross-bar or mud-guard h^9 a tube D or other section may be employed.

The backward continuation j of the mud- 25 guard is attached to the mud-guard h^9 and to the frame II by a bolt j' , fixed to such backward continuation j and passing through a hole in the mud-guard or cross-bar h^9 and

stampings or forging h^7 and secured thereto by nut j^2 .

30

Having now particularly described and ascertained the nature of my said invention and in what manner the same is to be performed, I declare that what I claim is—

1. In the manufacture of the diamond- 35 shaped frame of Safety bicycles, the combination of pairs of rods or bars h h' h^2 h^3 of trough-shaped or felly steel, stampings or forgings to connect them together at the angles, distance-pieces h^6 , and cross-bar or mud- 40 guard h^9 , connected to the top and bottom forgings or stampings, substantially as herein shown and described.

2. In Safety bicycles, the combination of a diamond-shaped frame of trough-shaped 45 metal with an upward extension of the cross- bar or mud-guard h^9 , forged into tubular shape and fitted to receive the pillar or support for the saddle or seat, substantially as herein shown and described.

WILLIAM HILLMAN.
